[57] **CLAIM**

The ornamental design for a case for audible signal

generator for enuresis prevention training device, as shown and described.

DESCRIPTION

FIG. 1 is a front elevational view of a case for audible signal generator for enuresis prevention training device showing my new design wherein the clip opens toward the right side of the case;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a sectional view taken along line 7—7 of FIG. 2;

FIG. 8 is a front elevational view of a case for audible signal generator for enuresis prevention training device showing my new design wherein the clip opens toward the left side of the case;

FIG. 9 is a rear elevational view thereof;

FIG. 10 is a top plan view thereof;

FIG. 11 is a bottom plan view thereof;

FIG. 12 is a left side elevational view thereof;

FIG. 13 is a right side elevational view thereof; and

FIG. 14 is a sectional view taken along line 14—14 of FIG. 9.
